(57) **CLAIM**

The ornamental design for an electronics enclosure, as
shown and described.

DESCRIPTION

FIG. 1 is a perspective view of the electronics enclosure;
FIG. 2 is a front view of the electronics enclosure of FIG. 1;
FIG. 3 is a right side view of the electronics enclosure of
FIG. 1;

FIG. 4 is a left side view of the electronics enclosure of FIG.
1; and,

FIG. 5 is a top view of the electronics enclosure of FIG. 1.
The broken line showing of the environment is for illustrative
purpose only and forms not part of the claimed design.

1 Claim, 5 Drawing Sheets

FIG. 1

FIG. 2

FIG. 3

FIG. 4

FIG. 5
